UNITED STATES PATENT OFFICE.

JOHN W. BRAY, OF LEEDS, ENGLAND.

BURNER FOR INCANDESCENT GAS-LIGHTING.

SPECIFICATION forming part of Letters Patent No. 790,714, dated May 23, 1905.

Application filed September 6, 1904. Serial No. 223,546.

To all whom it may concern:

Be it known that I, JOHN WILLIAM BRAY, a subject of the King of Great Britain and Ireland, residing at Leeds, county of York, 5 England, (whose post-office address is Bagby Works, Leicester Place, Leeds, aforesaid,) have invented certain new and useful Improvements in and Relating to Burners for Incandescent Gas-Lighting, of which the following 10 is a specification.

This invention relates to improvements in burners for incandescent gas-lighting, and is a development of the kind of burner-head or tip described and set forth in my Letters Patent No. 750,018, of January 19, 1904.

According to my former patent a burner head or tip of non-corrosive material was combined with wire-gauze immediately in contact with the under side of the burner head 20 or tip.

My present invention relates to a novel form of tip, in which wire-gauze is not required.

My improved head or tip is made in two series or layers of vertical orifices, the orifices being, preferably, substantially rectilineal, both layers of orifices being formed in the same piece of non-corrosive material or in two superposed layers thereof. The bottom layer 30 of orifices takes the place of and is equivalent to the wire-gauze diaphragm M described in my above-named patent and has much smaller and more numerous orifices than the top layer. The orifices in the top layer are 35 made larger than in the bottom layer, so as to allow of the free passage of the air and gas to the point of ignition after passing through the lower layer of smaller and more numerous orifices, which, as before stated, is substituted 40 for the before-referred-to wire-gauze.

In burner heads or tips made according to my specification No. 750,018, of 1904, in order to prevent "lighting back" wire-gauze of suitable mesh is inserted immediately below and in contact with the said burner head or tip. This wire-gauze is liable to corrode and is also liable to have adhere to it dust and other moving particles which pass up with the atmosphere. It is also further liable to be 45 come deranged, and thus permit lighting back.

All these several features impair the value of the burner head or tip, whereas my improved burner head or tip, constructed entirely of non-corrosive material, such as "potters' clay," and preferably in one piece, prevents 55 lighting back, and dust or other moving particles will not readily adhere to the non-corrosive material of which this burner head or tip is made, as it does to the metallic wire-gauze, and there is no possibility of the lower 60 layer of orifices becoming deranged like wire-gauze.

In describing my invention in detail, reference is made to the accompanying sheet of drawings, similar letters indicating similar 65 parts, in which—

Figure 1 is a plan of the top of the tip. Fig. 2 is a plan of the under side of the tip. Fig. 3 is an elevation of the tip. Fig. 4 is a sectional elevation showing the tip placed in 70 position in the metal socket hereinafter referred to, and Fig. 5 is a sectional plan.

In carrying out my invention I prefer to construct the burner-tip A of potters' clay and give the desired form to the tip by stamping or molding in presses usually employed for this class of work; but if I use a material such as steatite the requisite form may be given to the tip by the usual process of turning and drilling or other convenient shaping 80 processes.

I make one, two, or more concentric circles of orifices B in the top layer C of the tip A, such orifices being, by preference, substantially rectilineal, as described in the above-mentioned specification. If there be two concentric circles of orifices B in the top layer C, as shown in the drawings, I form in the bottom layer D, by similar means by preference, four circles of similar but smaller orifices E, as 85 shown in the drawings, these lower orifices E taking the place of the metallic wire-gauze as hitherto used.

In order to carry or support the mantle-rod, a hole F is formed by any convenient 95 means in the center of the tip A and grooves G formed in the walls of the said hole F for the purpose of carrying a clip, such as described in my specification No. 750,018, of 1904. The tip A of non-corrosive material 100

may be mounted in a socket or tube of metal and be detachable from the burner.

Where the concentric layers C and D of the vertical orifices are in two separate plates, as shown by the dotted line in Fig. 4, I mount these two together in one tube or socket and confine them in juxtaposition by flanging or spinning suitable projections in the metal of the tube H, as shown at J and K in Fig. 4.

10 What I claim as my invention is—

1. As a new article of manufacture, a tip for incandescent gas-burners having a series of orifices for the escape of the gas, and a screen made integral with the tip, substantially as described.

15 2. As a new article of manufacture, a tip for incandescent gas-burners having a series

of orifices for the passage of gas, and a partition extending across each orifice forming an integral screen, substantially as described. 20

3. The combination in a tip for gas-burners made of non-corrosive material and of a single piece having orifices for the passage of gas, partitions extending across the lower portions of the orifices, and a central tubular section to receive the mantle-support, substantially as described. 25

In witness whereof I have hereunto set my hand in the presence of two witnesses.

JOHN W. BRAY.
